HARRY C. BREWSTER, OF SHREVEPORT, LOUISIANA.

DRAW WORKS.

Application filed October 13, 1923. Serial No. 668,316.

To all whom it may concern:

Be it known that I, HARRY C. BREWSTER, a citizen of the United States, and resident of Shreveport, in the parish of Caddo and State of Louisiana, have invented certain new and useful Improvements in Draw Works, of which the following is a specification.

This invention relates to draw works, especially adapted for use in connection with the rotary system of drilling.

In the draw works now generally in use, three main supports are provided for the drive shaft and because of the normal position of the drum the placing of a supporting post at the intermediate portion of the drive shaft is impossible, and therefore the intermediate portion of the drive shaft is frequently sprung.

Therefore an important aim of this invention is to so organize the draw works that the intermediate portion of the drive shaft is effectively braced whereby it will not be sprung during use and will operate with a minimum of vibration and wear.

A further object is to provide a draw works wherein the same is provided with a novel form of foundation or base so that it may be securely and positively held in position.

A further object is to provide a draw works which is of highly simplified construction, durable in use and cheap to manufacture.

Other objects and advantages will be apparent during the course of the following description.

The accompanying drawings forming a part of this application, and in which like numerals are employed to designate like parts throughout the same,

Figure 1 is a side elevation of the improved draw works,

Figure 2 is an end elevation of the draw works.

In the drawings, wherein for the purpose of illustration, is shown a preferred embodiment of the invention, the numerals 5, 6, and 7 designate the main and original posts of the machine, and the numeral 8 designates the additional post which is so located that it is in line with the original posts 5, 6, and 7 so that it will effectively support and brace the drive shaft 10. In carrying out the invention, the drive shaft 10 is extended

through bearings 11 carried by posts 5, 6, and 7 and 8, and of course the bearings are all in line. Figure 1 illustrates that the main drive sprocket 12 which is keyed to the intermediate portion of the main drive shaft 10 is located close to the intermediate post 8 so that the strain incident to the drive through the wheel will not spring the shaft.

In the machine as now built, the drum 14 prevents the employment of the additional intermediate post 8 because the drum intersects the plane in which the posts 5, 6, and 7 are located. However, in accordance with this invention, the drum is not supported by the posts 5, 6, and 7, but is supported by inclined braces 16 and 17, the said braces being connected at the upper ends by bolts 18 to the posts 5, 6, and 7. The lower portion of the inclined bracing members 16 and 17 are connected to the upstanding branches 20 of metal brackets 22, the said brackets being extended across and secured to sills 24. One end of each bracket 22 is extended upwardly to provide an attaching portion 26 which is secured by bolts or other suitable means to the posts 5, 6 and 7. Due to the employment of the parallel sills 24, a wide base or foundation is provided by means of which an extremely rigid and durable construction is provided. The parallel sills 24 not only provide an extremely durable and rigid construction, but also constitute a supporting means for the inclined braces 16 and 17.

Attention is especially directed to the fact that the members 16 and 17 serve the dual purpose of bracing the end posts 5, 6 and 7 and of supporting the drum 14. This dual function performed by the inclined braces 16 and 17 makes possible the employment of the intermediate brace 8. More specifically, the inclined bracing members 16 and 17 rotatably support the drum 14 substantially in advance of the plane in which the main drive shaft 10 is located and this allows the posts 5, 6, and 7 and 8 to all be in the same plane.

In summarizing, it might be said that the inclined posts serve the following distinct purposes, all of which contribute to making the draw work much more rigid, durable and efficient than heretofore:

1. As a supporting means for the drum 14.
2. As a brace for the posts 5, 6 and 7.
3. As a means to space the drum 14 sub-

stantially in advance of the plane in which the posts 5, 6, and 7 are located, thus making it possible to have the posts 5, 6, and 7 and 8 all in the same plane.

5. As a means of distributing weight and strain over a larger foundation.

The usual power transmitting gears 28, 30, 31, and 32 may be employed without interference from the additional post 8 or 10 the inclined bracing and supporting members 16 and 17. Also the speed change mechanism may also be employed in the usual manner without being interfered with in any way.

15. Of course, the drilling rotary has connections by means of the usual sprocket chains with the gear 40.

With reference to the foregoing description taken in connection with the accompanying drawing it will be seen that a draw works constructed in accordance with this invention will effectively support the main drive shaft 10 at its intermediate portion so that springing or snapping of the shaft 25 is positively prevented. By reason of this construction and the other features mentioned the operation of the machine is rendered much safer and the wear on the parts is reduced to a minimum.

30. It is to be understood that the form of the invention herewith shown and described is to be taken as a preferred example of the same and that minor changes and arrangement and construction of parts may 35 be made as will remain within the spirit of the invention and the scope of what is claimed.

Having thus described the invention, what is claimed is:—

40. 1. A draw works for rotary well drilling comprising a plurality of spaced posts all arranged approximately in the same plane, a drive shaft rotatably carried by said posts, a drive member mounted on 45 said shaft adjacent one of said posts, a drum located immediately in advance of one of said posts, and a plurality of combined posts bracing and drum supporting members connected to certain of said posts and 50 spacing said drum substantially in advance of the intermediate post and brackets sup-

porting said combined post bracings and drum supporting members and connecting the same to said posts.

2. A draw works for rotary well drilling comprising a plurality of spaced posts all arranged in approximately the same plane, a drive shaft rotatably carried by said posts, a drive member mounted on said shaft adjacent one of said posts, a drum located in advance of one of said posts, a plurality of combined post bracing and drum supporting members connected to certain of said posts and spacing said drum substantially in advance of the intermediate posts, 65 supporting brackets connected to certain of said posts and supporting said combined post bracing and drum supporting members and a plurality of spaced parallel sills connected to said brackets and defining a 70 wide supporting foundation.

3. The combination with a plurality of main posts, of an additional bracing post arranged between said main posts and in the plane of the same, inclined bracing members 75 connected to the main posts, a drum supported solely by said bracing members and arranged substantially in advance of the additional post, a main drive shaft rotatably carried by said main and additional 80 post and having a drive member located adjacent said additional post, and brackets projecting from said main posts and supporting said bracing and drum supporting members.

85. 4. The combination with a plurality of main posts, of an additional bracing post arranged between said main posts and in the plane of the same, inclined bracing members connected to the main posts, a 90 drum supported solely by said bracing members and arranged substantially in advance of the additional post a main drive shaft rotatably carried by said main and additional 95 posts and having a drive member located adjacent said additional post, and brackets projecting from said main posts and supporting said bracing and drum supporting members, and sills connected to said brackets and defining a wide supporting 100 foundation.

HARRY C. BREWSTER.
